UNITED STATES PATENT OFFICE.

FRED ISRAEL WALKER, OF BABYLON, NEW YORK.

DEPTH-GAGE.

1,009,605.

Specification of Letters Patent. Patented Nov. 21, 1911.

Application filed September 24, 1910. Serial No. 583,599.

To all whom it may concern:

Be it known that I, FRED I. WALKER, a citizen of the United States, and a resident of Babylon, in the county of Suffolk and State of New York, have invented a new and Improved Depth-Gage, of which the following is a full, clear, and exact description.

The invention is an improvement in depth gages, particularly such as embody a stem or blade frictionally engaged and slideable in keepers pressed from and to the opposite sides of the gage head.

The invention has in view a depth gage of this character in which the keepers are set back a substantial distance inward from the working edges of the head, and the metal at these edges brought well to the blade so that the gage head will rest evenly substantially throughout on the surface to which it is presented, and will not be raised therefrom when the head is laterally tilted.

Another object of the invention is to provide for the frictional adjustment of one or more of the keepers to the blade.

A further object of the invention is to extend the metal of the head at the center well to the blade and provide the same with a graduated scale, and locate the said scale so that it will serve to give the correct reading of the blade when the head is in one position of use or the inverted position.

Reference is to be had to the accompanying drawings forming a part of this specification, in which similar characters of reference indicate corresponding parts in all the views.

Figure 1 is a front side view of a depth gage constructed in accordance with my invention; Fig. 2 is a rear side view of the same; Fig. 3 is a cross-section of the gage on the line 3—3 of Fig. 1; Fig. 4 is an inverted plan of the gage as shown in Fig. 1; Fig. 5 is a cross-section of the gage on the line 5—5 of Fig. 1; and Fig. 6 shows the head of the gage inverted, as when the gage is used in close places.

The type of gage to which I apply my improvements is well known and embodies a gage head 5, and a gage blade or stem 6, the head having a relatively long working edge 7 at one end, and a much shorter working edge 8 at its opposite end, and provided with a number of keepers 9 pressed to the opposite sides thereof in alternate order, in which the blade or stem is slideable and frictionally retained against accidental move-

ment. The keepers 9 in this type of gage generally adjoin the working edges, which prevents the metal of the head from being brought well up to the gage stem at these points, and also causes the head to be raised from the surface to which it is presented when the head is tilted laterally. To overcome this and make the edges of the metal of the head to extend well up to the gage stem, I position the outer keepers 9 a substantial distance inwardly of the working edges, making these edges substantially continuous, which is very desirable in practical use. A gage of this type is often rendered useless by the loosening of the gage stem in the keepers, due to the wear. To overcome this and provide for the requisite friction on the gage stem, I split one or more of the keepers 9, preferably the long central keeper 75 on the rear face of the head, as shown in Figs. 3 and 4, the slit in this keeper being adjacent to the body of the head so that the metal at this edge can be flattened out and brought well to the blade at the opposite 80 side, as indicated at 10 (see Figs. 1, 3 and 6.) This central or intermediate portion of the gage head which is extended well to the blade is, as shown in Figs. 1 and 6, graduated in any standard unit of measurement 85 and fractional parts of the said unit. The blade 6 is also graduated in the same unit, the lines of graduation 11 extending completely thereabout, so that they will at all times be presented to the scale when opposite 90 thereto, in any position the blade is turned, the positioning of the scale well up to the blade obviously adapting the reading to be correctly made. The scale is placed exactly centrally between the working edges 7 and 8 of the gage head so that it is adapted for use when the head is applied to the blade as shown in Fig. 1, as well as applied when shown in Fig. 6.

In the drawings the blade 6 is shown to be 100 marked every half inch from the lower end by the graduations 11 and as the head 5 has graduations thereon of thirty-seconds of an inch, the half inches may be read directly from the blade and the fractional thirty- 105 seconds may be read from the head, which will cause the projection of the blade to be read to a thirty-second of an inch.

Having thus described my invention, I claim as new and desire to secure by Letters Patent:

1. The combination of a depth gage head

having keepers pressed therefrom to the opposite sides thereof, and a depth gage blade 5
slidable and frictionally retained in the keepers, with the keepers arranged inwardly
from the working edges of the head, and
with the material of the head brought well
up to the blade.

2. The combination of a depth gage head
having keepers pressed therefrom to the opposite sides thereof, and a depth gage blade
10
slidable within and frictionally engaged by the keepers, one of the said keepers being
split whereby it may be adjusted to vary
the frictional engagement with the blade.

15 3. The combination of a depth gage head
having keepers stamped therefrom to the opposite sides thereof, and having working
edges at both ends, and a blade slidable
within and frictionally engaged by the

keepers, the head having a scale arranged 20
to give the correct reading of the blade for
either of the said working edges.

4. The combination of a depth gage head
having keepers stamped therefrom to the opposite sides thereof, and a depth gage 25
blade slidable within and frictionally en-
gaged by the keepers, the intermediate por-
tion of the head at one side opposite one of
said keepers brought well to the blade and
provided with a scale to give the reading of 30
the blade.

In testimony whereof I have signed my
name to this specification in the presence of
two subscribing witnesses.

FRED ISRAEL WALKER.
